FIG. 5

UNITED STATES PATENT OFFICE.

FREDERICK E. GERSTENBERGER, OF SOUTH EUCLID, OHIO.

METHOD AND MEANS FOR HEATING BY CARBON AND HYDROCARBON OILS.

1,382,721.

Specification of Letters Patent. Patented June 28, 1921.

Application filed January 12, 1918. Serial No. 211,541.

To all whom it may concern:

Be it known that I, FREDERICK E. GERSTENBERGER, a citizen of the United States, and resident of South Euclid, in the county 5 of Cuyahoga and State of Ohio, have invented certain new and useful Improvements in Methods and Means for Heating by Carbon and Hydrocarbon Oils, of which I hereby declare the following to be a full, 10 clear, and exact description, such as will enable others skilled in the art to which it appertains to make and use the same.

The objects of the invention are to provide an improved method and means for 15 producing heat from the consumption of carbon and hydrocarbon fuel oils, and gases and comprises first the production of combustible gases from said fuel, by first, heating them over an incandescent heating element, preferably electrical, and then permitting the heated gases to expand in a 20 closed chamber and afterward burning the rarefied gases in connection with a powerful blast.

25 The invention is exemplified in a heating device in which the essential features are embodied, and is illustrated in the accompanying drawings, and is hereinafter more fully described and specifically pointed out 30 in the claims.

In the accompanying drawings Figure 1 is a vertical section of a complete unit, including a blower, a heating element for fuel, and a closed chamber or retort in which the 35 heavy gases evolved from the fuel are expanded and rarefied, to put them in condition for immediate combustion. Fig. 2 is a form of construction showing feed tubes for oil or pulverized carbon and gas and 40 steam or air under pressure. Fig. 3 shows a modified form of construction for a heating unit, in which the pressure at the burner jet is obtained by the expansion of the combustible gases. Fig. 4 is a section of a portable form of heater for domestic use. Fig. 45 5 is an enlargement of the same.

In these views A is a feed tube for fuel oil such as crude oil or coal oil which falls from a receptacle B by gravity upon a pre- 50 heating element C, which is preferably heated to incandescence by means of an electrical current such as supplied by the battery D.

The preheating element is inclosed within the draft tube or passagé E supplied with air under pressure by means of a blower F 55 and the heated oil is resolved into a heavy

gas or gray smoke which enters the expanding chamber G, in which it becomes rarefied into light and heavy portions, and the heavy portions descend to the lower end of the 60 chamber G, where they become superheated and issue through the perforations G¹ as an inflammable gas and are lighted and consumed at that point. As soon as lighted the flame is turned upward about the expanding chamber by means of the deflector H, which becomes heated to incandescence and the heat generated thereby superheats the chamber and also superheats and rarefies the 65 heavy hydrocarbon gases in this chamber so that finally when they issue through the perforations and come in contact with the incandescent deflector H, perfect combustion will take place and the flame will become delicately violet. Any oil which is not decomposed flows into marginal troughs K and K and when superheated also becomes combustible gas. The lighter gases which are 70 already combustible issue through the perforations G² at a higher level and are there 75 consumed.

The fuel oil not yet completely gasified and remaining in the expanding chamber is rarefied by the excessive heat generated by the burner flame and becomes a combustible 80 gas which burns substantially without odor at the perforations.

The burner thus constructed becomes a unit which can be inclosed within the casing of a hot air furnace, a stove or other heater, 85 and can be applied to many useful domestic purposes without departing from the spirit of the claims.

Powdered coal can be employed as fuel alternately with the oil by introducing it 90 into the fan in a passage S. See Fig. 1.

In Fig. 3 a modified form is shown in which a corresponding superheating and expanding chamber M is employed and the gas generated therein passes through a pipe 100 L to a burner jet N controlled by a valve, N', regulating the size of the jet orifice and when ignited the jet plays upon the outer surface of the expanding chamber, and other parts remain substantially unchanged. In 105 Fig. 2 jet openings are provided for carbon oil and steam or air under pressure and a separate inlet for gas, so that powdered carbon or oil, or gas and steam, or compressed air can be employed simultaneously or separately, at will, to project the fuel against 110 a preheating element to rarefy the same,

prior to finally converting the same into a combustible gas and consuming the same under pressure. In Figs. 4 and 5 a portable domestic stove is illustrated, including a casing W. In Fig. 5, the fuel inlet pipe, E, is central, and is funnel-shaped and continuous with a base connecting it with the casing W. A fan, F, produces an upward circulation of air, and the motor which drives it is supported within the casing. A valve upon the oil supply pipe is also arranged to close the circuit to the motor when the valve is opened.

The combination of the forced draft with the rarefied and gaseous material produces an intense heat and utilizes a great percentage of heat units that would otherwise be lost.

These devices are particularly adapted for domestic uses and provide an increased amount of economy in the use of gas and fuel.

Having described the invention what I claim as new and desire to secure by Letters Patent is:—

1. In a domestic oil heater, a hollow casing, provided with air openings at the top and bottom, a fuel admission pipe having a funnel-shaped base and having a vertical central opening and marginal openings at the wider end for air entrance to the casing, an expanding chamber into the upper end of which fuel oil is discharged, an annular drip-trough in said chamber, in which unvaporized oil is deposited, said chamber provided with perforations adjacent to its lower end, through which heavier gases escape, and a deflector for flames issuing from said openings.
2. In a domestic oil heater, a hollow casing, provided with air openings at the top and bottom, a fuel admission pipe having a funnel-shaped base and having a vertical central opening and marginal openings at the wider end for air entrance to the casing, an expanding chamber into the upper end of which fuel oil is discharged, an annular drip-trough in said chamber, in which unvaporized oil is deposited, said chamber provided with perforations adjacent to its lower end, through which heavier gases escape, and a deflector for flames issuing from said openings.

- 45 3. In a domestic oil heater, a hollow casing, provided with air openings at the top and bottom, a fuel admission pipe having a funnel-shaped base and having a vertical central opening and marginal openings at the wider end for air entrance to the casing, an expanding chamber into the upper end of which fuel oil is discharged, an annular drip-trough in said chamber, in which unvaporized oil is deposited, said chamber provided with perforations adjacent to its lower end, through which heavier gases escape, and a deflector for flames issuing from said openings.
- 50 4. In a domestic oil heater, a hollow casing, provided with air openings at the top and bottom, a fuel admission pipe having a funnel-shaped base and having a vertical central opening and marginal openings at the wider end for air entrance to the casing, an expanding chamber into the upper end of which fuel oil is discharged, an annular drip-trough in said chamber, in which unvaporized oil is deposited, said chamber provided with perforations adjacent to its lower end, through which heavier gases escape, and a deflector for flames issuing from said openings.
- 55 5. In a domestic oil heater, a hollow casing, provided with air openings at the top and bottom, a fuel admission pipe having a funnel-shaped base and having a vertical central opening and marginal openings at the wider end for air entrance to the casing, an expanding chamber into the upper end of which fuel oil is discharged, an annular drip-trough in said chamber, in which unvaporized oil is deposited, said chamber provided with perforations adjacent to its lower end, through which heavier gases escape, and a deflector for flames issuing from said openings.

In testimony whereof, I hereunto set my hand this 8th day of November, 1917.

FREDERICK E. GERSTENBERGER.

In presence of—

Wm. M. MONROE,
CHAS. F. SIPE.
